RACK

Otto Krueger, Milwaukee, Wis.

Application April 22, 1935, Serial No. 17,713

2 Claims. (Cl. 24—66)

My invention relates to a rack for removably holding circulars, newspapers or other articles for which it is found applicable, and is designed primarily to be anchored to the panel of a door below or at other points in close proximity to a mail slot or box.

The essential objects of my invention are to provide, in a manner as hereinafter set forth, a rack for the purpose referred to which includes hanger elements for off-setting the body of the rack from and to prevent said body from damaging the support to which it is anchored; which is so formed as to enable the expeditious and convenient positioning of circulars, newspapers or other articles within the body of the rack; which is formed with resilient coacting means for frictionally clamping the articles positioned therein against accidental removal; which is thoroughly efficient in its use; which may be quickly anchored to a support therefor; and to attain these ends in a simple, strong, durable, compact, inexpensive structure.

To the above ends essentially and to others which may hereinafter appear, my invention consists of such parts and such combination of parts which fall within the scope of the invention as claimed.

In the drawing:

Figure 1 is a front elevation of the rack anchored to a support therefor,

Figure 2 is a side elevation of the rack anchored to a support, the latter being shown in section, and

Figure 3 is a perspective view of the rack.

By way of example, the rack 4 is illustrated as being anchored to the panel 5 of a door, but it is to be understood that it may be anchored to any suitable support. When anchored, it is to be positioned in close relation to a mail box (not shown). Preferably the rack 4 will be arranged a suitable distance below the mail box.

The rack 4 includes a skeleton body portion set up from a single length of wire of the desired gauge having its ends suitably connected together, as at 6, preferably by welding. The wire is bent or formed in a manner to provide the body portion with a back section 7, a two part bottom section 8 and a resilient front section 9. The section 7 is of inverted yoke-shape and flared. The section 8 is substantially of semi-circular contour. The section 9 is of inverted yoke-shape and flared and of greater length than section 7.

The section 8 is open at its top and is formed of two parallel spaced semi-circular upstanding

stretches 10, 11 of the endless wire disposed at right angles to the sections 7, 9.

The section 7 is formed from a horizontally disposed stretch 12 and a pair of upstanding stretches 13, 14 of the endless wire. The stretches 13, 14 have their upper portions outwardly inclined. The upper ends of stretches 13, 14 merge into the ends of the stretch 12. The lower ends of the stretches 13, 14 merge into the rear ends of the stretches 10, 11 respectively.

The section 9 is formed from a horizontally disposed arcuate stretch 15 and a pair of upstanding stretches 16, 17 of the endless wire. The stretches 16, 17 are of greater length than the stretches 13, 14 and extend above the stretch 12. The stretches 16, 17 have their upper portions inwardly inclined. The upper ends of stretches 16, 17 merge into the ends of the stretch 15. The lower ends of the stretches 16, 17 merge into the outer ends of the stretches 10, 11 respectively. The lower portions of the stretches 16, 17 are arranged in parallel spaced relation to the lower portions of the stretches 13, 14 respectively. The upper portions of the stretches 16 and 17 are disposed inwardly of the upper portions of the stretches 13, 14 respectively. The stretches 16, 17, from their lower to their upper ends, incline towards the stretches 13, 14 respectively. The stretch 15 is disposed from its bottom to its top upon a slight curve which is disposed outwardly with respect to the stretches 16, 17. In proximity to their lower ends the stretches 16, 17 have secured thereto the ends of a flat combined coupling and bracing member 18. The member 18 is of a width to receive suitable indicia, not shown, upon its outer face. The member 18 is positioned at the outer face of section 9.

The sections 7, 8 and 9 are arranged relative to each other to provide the body portion with what may be termed a pair of spaced parallel upstanding article receiving grooves 19.

The rack includes a pair of spaced parallel suspension elements 20, 21 which are arranged at the rear of the stretch 12, whereby the said elements are offset with respect to the said stretch. Each element includes a vertical shank 22 merging at its upper end in the bottom of an eye 23. The lower end of shank 22 is welded to the back edge of stretch 12. The elements 20, 21 are positioned in proximity to each side of the transverse median of stretch 12. The elements 20, 21 are for the passage of holdfast means 24 to anchor the rack to support 5.

The stretches 13, 14, from their upper to their lower ends, incline forwardly, and in connection

with the offsetting of the elements 20, 21 relative to stretch 12, provide for the body portion of the rack being completely spaced outwardly with respect to the support to which the rack is anchored.

What I claim is:

1. A rack comprising a skeleton back section, a skeleton bottom section and a skeleton front opposing section, spaced from and extending above the back section, said back and front sections being of inverted substantial U-shape and connected together at their lower ends by said bottom section, said back section being of flared contour, said front section being of tapered contour and having the upper portion of its sides inset with respect to the upper portion of the sides of the back section, said back section inclining forwardly from its upper to its lower end towards said bottom section, said front section inclining rearwardly from its lower to its upper end towards said back section, a flat narrow combined coupling and bracing member of rectangular form extending transversely of said front section and having its ends anchored to the lower portion of the sides of the front section in proximity to said bottom section, and a pair of spaced apertured upstanding parallel hanger elements offset with respect to the top of said back section for the passage of holdfast devices to anchor the rack to a support, said elements having their lower ends secured to the rear edge of the top of said back section for offsetting the latter throughout in spaced relation with respect to the support.
2. A rack comprising a skeleton back section,

a skeleton bottom section and a skeleton front opposing section, spaced from and extending above the back section, said front and back sections being of inverted substantial U-shape and connected together at their lower ends by said bottom section, said back section being of flared contour, said front section being of tapered contour and having the upper portion of its sides inset with respect to the upper portion of the sides of the back section, said back section inclining forwardly from its upper to its lower end towards said bottom section, said front section inclining rearwardly from its lower to its upper end towards said back section, a flat narrow combined coupling and bracing member of rectangular form extending transversely of said front section and having its ends anchored to the lower portion of the sides of the front section in proximity to said bottom section, and a pair of spaced apertured upstanding parallel hanger elements offset with respect to the top of said back section for the passage of holdfast devices to anchor the rack to a support, said elements having their lower ends secured to the rear edge of the top of said back section for offsetting the latter throughout in spaced relation with respect to the support. 5 10 15 20 25
